United States Patent Office

Des. 215,546
Patented Oct. 7, 1969

215,546

COVER FOR DATA COMMUNICATIONS APPARATUS

Donald M. Genaro, Haworth, N.J., assignor to Teletype Corporation, Skokie, Ill., a corporation of Delaware

Filed July 5, 1968, Ser. No. 12,646

Term of patent 14 years

Int. Cl. D14—02

U.S. Cl. D26—5

FIG. 1

FIG. 2

FIG. 3

FIG. 4

FIGURE 1 is a front perspective view of a cover for data communications apparatus showing my new design;

FIGURE 2 is a right side view thereof;

FIGURE 3 is a rear view thereof; and

FIGURE 4 is a top view thereof.

The broken lines are shown for illustrative purposes only.

I claim:

The ornamental design for a cover for data communications apparatus, substantially as shown and described.
